INVENTOR.
Louis Rinaldo
BY *Henry J. Webster*
ATTORNEY

UNITED STATES PATENT OFFICE.

LOUIS RINALDO, OF STOCKTON, CALIFORNIA.

WORKING SHOE.

Application filed June 20, 1923. Serial No. 646,500.

To all whom it may concern:

Be it known that I, LOUIS RINALDO, a subject of Italy, residing at Stockton, county of San Joaquin, State of California, have invented certain new and useful Improvements in Working Shoes; and I do declare the following to be a full, clear, and exact description of the same, reference being had to the accompanying drawings, and to the characters of reference marked thereon, which form a part of this application.

This invention relates to improvements in the leather shoe-making art, and particularly to a type of shoe especially adapted for heavy work and rough usage such as they are subjected to by miners and all pick-and-shovel men, workers in logging camps and around the mountains generally, and by all men employed in what may be termed rough occupations.

The principal object of my invention is to provide a shoe especially made for working purposes for such men, and so constructed that it will stand severe usage without any seams ripping out or necessitating repairs other than those called for by natural wear.

Another object is to build up the sole portion of the shoe in such a manner that a main or base sole piece, extending the full length of the shoe, is provided which never becomes worn out during the life of the shoe, but always forms a fresh and new surface to which to attach any new half-sole pieces after the original one has worn out, said half-sole being a separate piece from the base sole piece.

A further object is to produce a simple and inexpensive shoe for the purpose, and yet one which will be extremely efficient in the service for which it is intended.

These objects I accomplish by means of such structure and relative arrangement of parts as will fully appear from a perusal of the following specification and claim.

On the drawings, similar characters of reference indicate corresponding parts in the several views.

Fig. 1 is a side elevation of the shoe.

Fig. 2 is a longitudinal section thereof.

Fig. 3 is a cross-section through the heel on the line 3—3 of Fig. 2.

Fig. 4 is a perspective view of one of the heel-fillers.

Referring now more particularly to the numerals of reference on the drawings, the numeral 1 denotes the forward upward por-

tion of the shoe, in which the forward portion of the foot is encased, and extending substantially for half the length of the shoe at its lower edges. A centrally positioned tongue piece 2 is formed integral with the member 1. The remainder of the upper portion of the shoe, to the rear of the member 1, is formed of another single piece of leather 3, open or split at its forward edges, and overlapping the tongue 2 and the adjacent lower end of the member 1, being there sewed to said member 1 as at 4. A counter 5 extends part way around the piece 3 inside the same along its lower portion.

One forward edge of the piece 3 is provided with integral straps 6, adapted to overlap the opposed forward edge of said member and to then cooperate with buckles 7 fixed on the latter. The tongue 2 extends about to the top of the member 3.

The sole and heel structure is built up as follows. A relatively thin insole 8 occupies the usual position inside the shoe. Below this is placed a thicker but narrower filler 9, feathering toward its edges, and extending about half the length of the shoe from adjacent the back of the heel forwardly. Below this filler is a strip 10, about the same length as the piece 9, but of equal cross-section throughout, and the full width intended for the sole. Below the strip 10 is the main or base sole member 11, the same width as the strip 10, and extending the entire length of the shoe, this sole bearing 90 against the strip 10 and against the insole 8 beyond said strip. The latter being somewhat thick, an offset or step as shown in Fig. 2 is formed in the sole 11 at the forward end of the piece 10, extending transversely 95 of the shoe, and from this offset to the toe of the shoe, the outer half-sole 12 extends, forming the actual ground bearing portion of the sole structure, and the only member thereof which is ever subjected to any wear.

It will therefore be evident that when this half-sole is worn out, it may be easily removed without cutting or disturbing the main sole 11, which will remain in its original form, unworn, and a new half-sole may then be secured to this main sole, the shoe being then as good as new as far as the further wearing qualities of the sole as a whole are concerned.

The interposition of the filler 9 above the sole pieces 10 and 11 causes the latter to have a ridge, as shown in Fig. 3, extending for

the length of said piece 9, which if not counteracted at the heel, would prevent the main heel pieces 13 from having a good and flat contact with the sole. I therefore place 5 between said heel pieces 13 and the sole 11 one or more fillers 14 the shape of the heel around the periphery, but cut away in the middle so as to be substantially like a horse-shoe in shape, as shown in Fig. 4, the inner 10 periphery being tapered or feathered to conform to the slope of the abovementioned ridge. The total height of the piece or pieces 14 is equal to the height of the ridge, so that the heel pieces 13 will have firm support across their entire width, and will be 15 perfectly horizontal.

The lower edges of the upper shoe pieces 1 and 3 are turned inwardly between the insole 8 and the adjacent pieces outwardly 20 thereof, all the members being then nailed together.

The pieces 10 and 12 being cut from the same piece of leather, they are of course the same thickness, and the half sole 12 will 25 thus lie flush at its rear end with the main sole 11.

From the foregoing description it will be

readily seen that I have produced a shoe such as substantially fulfills the objects of the invention, as set forth herein. 30

While this specification sets forth in detail the present and preferred construction of the shoe, in practice such deviations may be made as do not depart from the spirit of the invention, as defined by the appended claim. 35

Having thus described my invention, what I claim as new and useful, and desire to secure by Letters Patent is:

In shoe construction, a flexible sole member, a filler strip above the sole extending 40 from the heel forwardly, said filler on its under side sloping up to relatively thin edges from its longitudinal center line whereby when applied to the sole the under face of the latter will be bent to have a 45 similar slope, a flat heel piece applied to the rear end of the sole, and a filler piece between said heel and the sole extending inwardly from the vertical faces of the heel piece to fill the wedge shaped space formed 50 between the flat heel piece and the bent sole piece.

In testimony whereof I affix my signature.
LOUIS RINALDO.
